UNITED STATES PATENT OFFICE.

EUGENE F. AHLQUIST, OF MINNEAPOLIS, MINNESOTA.

ENVELOPE.

Application filed December 27, 1924. Serial No. 758,354.

This invention relates to an improvement in envelopes, and has for its object to provide a new and improved device of this description. The invention has as a further object to provide an envelope which will be strong and durable, and arranged so that the back portion is reenforced so that there will be no projecting part which will catch on adjacent envelopes, partitions or other devices, and which might by such engagement be injured or torn loose. The invention has further objects which will be more particularly pointed out in the following description:

15 Referring now to the drawing,

Fig. 1 is a back view showing one form of envelope embodying the invention.

Fig. 2 is an end view of the envelope illustrated in Fig. 1.

20 Fig. 3 is an enlarged sectional view taken on line 3—3 of Fig. 1.

Fig. 4 is an enlarged sectional view taken on line 4—4 of Fig. 1.

Fig. 5 is a view of the corner of the 25 envelope with the parts separate.

Fig. 6 is a view similar to Fig. 5 showing the method of connecting the parts.

Fig. 7 is a view showing a modified construction.

30 Fig. 8 is an enlarged sectional view taken on line 8—8 of Fig. 7.

Fig. 9 is an enlarged sectional view taken on line 9—9 of Fig. 7.

Fig. 10 is a view of the corner of the 35 envelope showing the parts separate.

Fig. 11 is a view similar to Fig. 10 showing the method of assembling the parts.

Referring now to the drawings, I have shown my invention as applied to an envelope of the expansion type. In this construction the envelope is provided with a

40 front portion 1 and a back portion 2, said portions being connected at their ends and bottom by the connecting member 3, which

45 in this instance is shown as an expansion member. The back portion 2 is provided with a flap 4, which passes over and covers the upper portion of the envelope in the usual way. The connecting member 3 is

50 provided with the connecting piece 5 by means of which it is connected with the front and back portions of the envelope, the connection usually being made by some adhesive material, these connecting pieces

55 being substantially parallel with the front and back portions 1, being illustrated in

dotted lines in Fig. 1. In the construction as shown in Figs. 1 to 4 inclusive, the back portion 2 at each end is provided with a slot 6 clearly shown in Fig. 5. This slot 66 is diagonal and runs to the top of the back portion thus providing a section 7, which may be bent out of alignment with the back portion. The main part of the back portion is on the outside of the connecting piece or 65 pieces 5 of the connecting element, while the section 7 is bent inwardly so as to be in the inside thereof, as shown in Fig. 3.

Fig. 5 shows the parts before they are assembled and Fig. 6 shows the parts as they 70 are being assembled, while Figs. 1, 3 and 4 show the parts after they are assembled. In the assembling of the parts the section 7 at each end of the back portion is bent inwardly and placed on the inside of connecting piece 5, the remaining portion of the back being on the outside of piece 5, and the parts are then connected together in any desired manner as by means of adhesive material.

75 It will thus be seen that when the parts are assembled, the connecting pieces 5 of the connecting member 3 are continuous so that the strength thereof is not diminished, and that the back portion has a part which 80 is bent out of the plane of the back or out of alignment therewith, and which engages a portion of the inner continuous face of the connecting piece 5, thus preventing the back from being pulled loose from the connecting 85 piece. It is important in this construction that the connecting piece 5 be continuous and unbroken at the point where the portion of the back which is on the inside thereof ends and the portion of the back which is 90 on the outside thereof begins, or vice versa.

95 It will further be noted that the edge of the back portion on the outside of the connecting piece 5 faces upward so that when the envelope is slipped down among other 100 envelopes or to the side of a partition or other obstruction there is no projection to catch thereon, the exterior face of the back portion projecting out further than the exposed portion of the connection piece.

105 In Figs. 7 to 11 I have shown a modified construction. In this construction the slot 6^a in the back instead of being diagonal or inclined runs substantially straight across the back as clearly shown in Fig. 10. This 110 provides a section 7^a of the back portion (see Figs. 10 and 11) which is received on

the inside of the connecting piece 5, the remaining portion of the back being on the outside thereof.

Fig. 10 shows the parts before they are assembled, and Fig. 11 shows the parts as they are being assembled.

Figs. 7, 8 and 9 show the parts after they are assembled.

It will be seen that in this latter construction the main part of the back portion 2 projects beyond the exposed portion of the connecting piece 5 so that there is no projection to catch when the envelope is slid down between other devices.

15 The section 7^a and the remaining part of the back portion is connected with the connecting piece 5 in some suitable manner as by adhesive material.

20 The inner lining 9 may be placed on the inside of the envelope if desired.

It will thus be seen that I have here provided an envelope reenforced at the point where such reenforcement is important and that I have secured this reenforcement by 25 simply providing a section of the back which is bent out of alignment with the remaining portion, and which engages the connecting piece 5, the connecting piece itself being continuous at the point which connects the main 30 portion of the back and the bent section thereof. By connecting the lower section of the back to the outer part of the connecting piece, I provide a construction which presents no obstruction when the envelope 35 is slipped down among other envelopes, or in a compartment. By attaching the upper section of the back to the inner side of the connecting piece, and connecting the flap with this section, I provide a strong reinforced envelope.

40 I claim:

1. An envelope comprising a front portion and a back portion, connecting pieces at the ends connecting the front and back portions together, said connecting pieces each having a portion which extends parallel with the back portion of the envelope and which is continuous, said back portion at the edge having two sections bent out of alignment, 45 one section attached to the outer portion of the connecting piece, and the other section attached to the inner portion of the connecting piece.

2. An envelope comprising front and back 50 portions, connecting pieces at the ends connecting the front and back portions together, said connecting pieces at each end having portions extending parallel with said back portion, said back portion at each end hav-

ing two sections out of alignment, the bottom 60 section being located on the outside of the connecting pieces, and the top section on the inside of said connecting pieces.

3. An envelope comprising front and back 65 portions, connecting pieces at the ends connecting the front and back portions together, said connecting pieces at each end having portions extending parallel with said back portion, said back portion at each end having two sections out of alignment, the 70 bottom section being located on the outside of the connecting pieces, and the top section on the inside of said connecting pieces, a flap connected with said back portion and having 75 its ends connected with the sections thereof on the inside of the connecting pieces.

4. An envelope comprising front and back 80 portions, connecting pieces at the ends connecting them together, the ends of the back portion being provided with slots near the top thereof, the connecting pieces being inserted in said slots, the portions of the end piece above the slots being attached to the inside of said connecting pieces and the portions of the end pieces below the slots being 85 attached to the outside of said connecting pieces.

5. An envelope comprising front and back 90 portions, connecting pieces at the ends connecting the front and back portions together, said connecting pieces at each end having portions extending parallel with the back 95 portions, said portions being continuous, all the parts of each portion being in the same plane, the edges of the back portion being provided with slots into which the parallel portions of the connecting pieces are received, and a flap connected with said back portion.

6. An envelope comprising front and back 100 portions connecting pieces at the ends connecting the front and back portions together, said connecting pieces at each end having portions extending parallel with the back portions, said portions being continuous, all the parts of each portion being in the same plane, the edges of the back portion being provided with slots into which the parallel 105 portions of the connecting pieces are received, and a flap connected with said back portion, said back portion when the parts are in position being flat and free from 110 projections.

Signed at Minneapolis county of Hennepin and State of Minnesota, this 14th day 115 of November, 1924.

EUGENE F. AHLQUIST.
